KNITTING MACHINE

Robert Evan Davis, Jr., Fort Payne, Ala., assignor to Interwoven Stocking Company, New Brunswick, N. J., a corporation of New Jersey

Application March 3, 1938, Serial No. 193,622

9 Claims. (Cl. 66—41)

My invention consists in the novel features hereinafter described, reference being had to the accompanying drawings which illustrate an embodiment of my invention, selected by me for purposes of illustration, and the said invention is fully disclosed in the following description and claims.

My invention is an improved circular or seamless knitting machine for knitting plain knit 10 seamless fabric by single feed and by multiple feed under the control of the pattern mechanism, and containing provision for incorporating an elastic thread under tension, fed to selected needles at one of the knitting stations, preferably 15 in association with an inelastic body thread fed at that station; to the end that portions of the seamless fabric, as the top of a stocking, may be formed of plain knitting with two, three or more courses knit simultaneously during each revolution of the machine, with the elastic thread under tension, incorporated preferably with one 20 of the body threads and secured to the fabric at spaced or separated points in each of the courses containing it, and floated on the inner face of 25 the fabric between said points so as to draw the fabric into a plurality of vertically disposed rib-like ridges, and thereafter the feeding of the elastic thread may be discontinued and other 30 portions of the tubular fabric, as the leg portion between the top and heel pocket and the foot portion between the heel and toe pockets may be 35 knit with one, two or more feeds, i. e., by single course or multiple course plain knitting, as preferred.

In carrying out my invention, the knitting machine is provided with a single circular series of vertically and independently movable needles, a main knitting cam which may be located permanently in the cam ring, for example, at the 40 throat plate which is provided with the usual plurality of thread feeding fingers, movable into and out of operative position, and a series of auxiliary knitting cams located at intervals around the circular series of needles, each operating in 45 association with a separate thread feeding finger (or fingers), the auxiliary cams and their associated feed fingers being capable of movement into and out of operative position under the control of the pattern mechanism, selected 50 needles being arranged to be brought to a different elevation from that of adjacent non-selected needles at one of the knitting stations, so that the selected needles may receive the elastic thread while the body thread may be fed to 55 all of the needles, and all of the needles receiv-

ing the additional body threads adjacent to the auxiliary knitting cams when in operation, to produce the intervening courses not containing the inelastic thread.

Where the elastic thread is incorporated during multiple course knitting as in the top of a stocking, it will be obvious that it will be incorporated continuously throughout the successive revolutions of the machine, so long as it is fed, but the course containing it will be spaced by the 10 intervening courses not containing elastic thread, and the stitches of each course will be knit into the stitches of a preceding and succeeding course formed of a different thread. The fabric produced by my improved knitting machine, and 15 the process of knitting the same, are not claimed herein, as they form the subject matter of a separate application filed by me January 15, 1938, and given Serial No. 185,122. The machine 20 embodying my invention herein illustrated and described, is particularly designed for the production of seamless plain knit hosiery, particularly men's socks and anklets, but is obviously adapted for the production of other forms of 25 seamless tubular fabric.

In the accompanying drawings which illustrate an embodiment of my invention selected by me for purposes of illustration:

Fig. 1 represents a partial front view of a knitting machine having my invention embodied 30 therein, partly broken away.

Fig. 2 is a side view of a portion of the machine, also partly broken away.

Fig. 3 is a plan view of the portion of the machine adjacent to the knitting cylinder and showing the parts associated therewith.

Fig. 4 represents a horizontal section on line 4—4 of Fig. 2.

Fig. 5 is a horizontal section through the sinker cap on line 5—5 of Fig. 2.

Fig. 6 is a vertical sectional view on line 6—6 of Fig. 3, parts being broken away.

Fig. 7 is a detail view partly in section, showing one of the auxiliary feeding fingers and the means for operating the same, parts being 45 broken away.

Fig. 8 is a view similar to Fig. 7 showing one of the auxiliary knitting cams and the mechanism for moving it into, and out of operative position, parts being broken away.

Fig. 9 is a diagrammatic view representing the cam ring cut at one point and spread out in a plane, as viewed from the outside of the ring, and also showing the needles and thread feeding fingers.

Fig. 10 is a detail view of one of the short butt needles provided with a shoulder above the butt.

Fig. 10a is a detail view of one of the short butt needles without such shoulder.

Fig. 11 is a detail view of one of the long butt needles provided with a shoulder similar to that shown in Fig. 10.

Fig. 11a is a detail view of one of the long butt needles without such shoulder.

10 The knitting machine shown in the accompanying drawings is one of the well-known Banner machines for knitting a complete sock or stocking, manufactured by the Hemphill Company of Pawtucket, Rhode Island, to which certain parts have been added, and in which certain parts have been changed, in order to adapt it for carrying out my present invention.

In these drawings, 1 represents the frame of the machine, provided with the rotary needle cylinder 2, carrying a horizontal gear wheel 3, engaging a driving gear 4, for rotating it in the usual manner for circular work, and for reciprocating it in the usual manner for reciprocating work. 5, 5a represent picker mechanisms for narrowing and widening, for formation of heel and toe pockets, and 6 represents the latch ring, pivotally supported in the usual manner, all of which, parts may be of usual or any desired construction, and form no part of my present invention. The needle cylinder 2, carries in its needle grooves a single vertical series of needles which are divided in the usual manner, one-half being provided with long butts, and the other half being provided with short butts, the short butt needles operating in the usual manner with the narrowing and widening mechanism to produce the heel and toe pockets under the control of the usual pattern mechanism, forming part of the machine. For the purpose of selecting 40 the needles which are to receive, and connect to the fabric the elastic thread, the needles of both kinds which are not to receive the elastic thread, are each provided with a shoulder above the butt, but of less radial extent than the butt. 45 For example, in Fig. 10, I have shown a needle having a short butt 7a, above which is the shoulder 7b, referred to, while in Fig. 10a, I have shown one of the needles 7, provided only with the short butt 7a. In Fig. 11, I have shown one 50 of the long butt needles provided with the long butt 8a, and shoulder 8b, immediately above the same, while in Fig. 11a, I have shown a long butt needle 8, provided with the long butt 8a, only. The separation of the points at which the elastic thread is to be secured in the fabric is determined by the positions occupied by the needles 7 and 8, which are not provided with shoulders, with respect to the shouldered needles. This separation may be every other needle 60 or a separation of two needles, three needles, or more, as may be desired. I have found that a desirable separation of the selected needles is secured by separating the selected needles 7 or 8, which do not have the shoulders, by three 65 intervening shouldered needles, as shouldered needles shown in the drawing, although this is not essential. I have also found it convenient to effect a separation of the needles, that is to say, bringing the hooks of the selected needles 70 (without shoulders) into a position to receive the elastic thread at a higher plane than that at which the intervening shouldered needles are brought at the time they receive the body thread, and this is most conveniently effected at the 75 main knitting cam indicated at 9 (see Fig. 9),

located in operative relation to the throat plate in the usual manner, this cam being provided with the auxiliary cams 9a, 9b and 9c, for circular and reciprocating work as usual in the Banner machines. The draw-down faces of cams 9, 5 9a, are in position to act upon the shoulders 7b, 8b, of the needles 7 and 8, and the nibs 7a and 8a, of the selected needles, so that it necessarily follows that the shouldered needles will be drawn downward at the main knitting cams, which I 10 conveniently term knitting station 1, (see Fig. 9) to a greater extent than the non-shouldered selected needles, as clearly indicated in Fig. 9. 10 represents the thread feeding finger for feeding elastic thread indicated at 11, and which in 15 this instance may be one of the throat feeding fingers which is normally maintained at a higher level than the adjacent thread feeding fingers for the body thread, one of which is indicated at 12, when in operative feeding position. It 20 will be noted that the selected needles will take the elastic thread 11, in their hooks at a higher point than that at which the body thread 13, is fed, and that the body thread is fed by the thread feeding finger 12, to all the needles, that 25 is to say, both the selected and non-selected or shouldered needles, as clearly indicated in Fig. 9. It will be understood that the throat plate will be provided with the usual plurality of thread guides 12, which can be thrown into and out of 30 operative position to feed body thread or threads to all the needles for striping, reinforcing and other purposes. The cam ring 14, is provided with one or more auxiliary knitting cams, and associated thread feeding mechanisms for feeding body thread to all of the needles in the same revolution of the machine when in operative 35 positions. In the drawings, I have shown the knitting cam ring provided with three auxiliary knitting cams and thread feeding mechanisms 40 for each, disposed at convenient intervals around the knitting cylinder, and constituting knitting stations 2, 3 and 4, and this is my preferred arrangement as it permits the formation of a single course of knitting when the auxiliary cams 45 are out of operative position, and the simultaneous formation of two, three or four courses, by throwing one or more of the auxiliary knitting cams into operation, but the particular number of auxiliary cams is not essential. The cam ring 50 14, is shown provided with the V shaped recesses indicated at 15, 16 and 17, in Fig. 9, associated with draw-down cams 18, 19 and 20 respectively, in a well-known manner, and cooperating with vertically movable thread feeding fingers 21, 22 55 and 23, cooperating respectively with said cams, 18, 19 and 20, to provide knitting stations 2, 3 and 4. Each of the radially movable draw-down cams, one of which, cam 20, is shown in section in Fig. 8, is carried by a horizontal slide 24, movable in a guide 25, radially with respect to the cylinder into and out of operative position. Each slide is provided with a retracting spring 26, tending to move it inwardly into operative position, and a stop 27, is provided for each of these 60 slides for arresting it in such a position that the cam carried thereby will engage the outer end portions of the butts of both the short butt and long butt needles exterior to the shoulders of the shouldered needles, as clearly shown in 70 Fig. 8, so that the auxiliary cams will draw down all of the needles of the circular series to the same extent. I prefer to make this stop adjustable to accommodate any variations in the needles which may occur from time to time, and to

this end, each of the slides 24, is provided with a slotted plate constituting the stop 27, adjustably secured to the slide by a screw 28, in position to engage the guide 25, and limit the inward movement of the cam.

The auxiliary thread guides 21, 22 and 23 will obviously be moved into and out of operative position simultaneously with their respective cams 18, 19 and 20. These auxiliary fingers are pivotally mounted on brackets 29, secured to the latch ring at suitable points around the same, so that they may be moved vertically into and out of operative position as indicated in Fig. 7, for example, which shows the finger 23, for the cam 20, at knitting station 4. Each of the feeding fingers is provided with a retracting spring 30, normally tending to draw the finger downward into operative position, and the fingers are raised into inoperative position, against the tension of this retracting spring 30, by a suitable mechanism hereinafter described. In the present instance, I have found it convenient to locate auxiliary cams 18 and 19 at points adjacent to the hinge pin 6a, of the latch ring 6, and the cam 20, is located on the opposite side of the cylinder (see Figs. 2, 3 and 4).

At one side of the machine (see Figs. 1 and 2) there is provided a cam wheel 31 mounted on a shaft 32, and provided with a series of cam grades 33, 34 and 35, on its cylindrical face for engaging tappet levers 36, 37 and 38, respectively, all of said tappet levers being pivotally mounted on a stationary pin 39, secured to the frame of the machine, and tappet levers 36 and 37 respectively, being provided with extensions 36a and 37a. The tappet levers in the construction herein shown, have their cam engaging ends on the side of the cylinder adjacent to knitting station 4, and almost directly below cam 20, and its feeding finger 23 (see Figs. 2, 7 and 8), and tappet 38 is provided with vertically movable rods 40 and 41, for controlling thread guide 23, and cam 20 respectively, both of said rods being pivotally connected to the tappet 38. The rod 40, as clearly shown in Fig. 7, extends upwardly to the thread feeding finger 23, and engages a stud 23a, on said finger, so that when the tappet 38, is raised by its cam grade 35, the finger will be thrown out of operative position as indicated in dotted lines, the rod 40, engaging a guide 40a, on the machine for maintaining it in proper relation with the stud 23a. The rod 41, is connected at its upper end with a bell-crank lever 42, pivoted to a suitable bracket 41a secured to the machine and having its upper arm engaging a stud 24a, on the slide 24, carrying the cam 20, so that the upward movement of the tappet 38, by its cam guide 35, will simultaneously withdraw the cam 20 and the thread finger 23, from operative position and when the tappet 38, passes off of the cam grade 35, the cam 20, and thread feeding finger 23, will be returned to operative position by their respective springs 26, and 30. Obviously, the similar control of the cams 18 and 19, which are on the opposite side of the machine, will be effected by a downward pull instead of an upward push. This movement is effected by the extensions 36a and 37a, of the tappets 36 and 37, and appropriate connections. Each of these extensions is provided with a pair of vertically disposed rods 43, 44 and 45, 46, for securing the simultaneous movement of the cams 18 and 19, and their respective thread feeding fingers out of and into operative positions by the cam guides 33 and 34. As the connecting mech-

anisms are the same for both of the cams 18 and 19, a description of one set of these connections will serve for both. Thus the extension 37a, of tappet 37, which operates auxiliary cam 19 and its associated thread feeding finger 22, has its 5 rod 44, pivotally connected at its upper end with a short lever 47, pivotally mounted on the pivot pin 22b, on which the finger 22, is mounted, this link 47, being provided with an extension on the other side of the pivot pin 22b, having a 10 lug 48, extending under the thread finger 22, so as to lift the finger into inoperative position when the rod 44, is drawn downward. The shorter rod 43, connected with the tappet extension 37a, is pivoted at its upper end to a bell-crank lever 49, 15 pivoted to the frame of the machine, and having an upwardly extending arm engaging a stud 24a, on the slide 24, carrying the auxiliary cam 19. In like manner the vertically disposed rods 45 and 46, extending upwardly from the tappet 36a, are operatively connected with the auxiliary cam 18, and the associated thread feeding finger 21, in exactly the same manner just described, the parts of said connections where indicated in the drawings, carrying the same reference numerals. It is desirable that the operative connections between the cam grades 33, 34 and 35 on the pattern wheel, and the several auxiliary cams and auxiliary thread guides should be so constructed as not to interfere with 30 the raising of the latch ring 6, on its pivot pin 6a, when that is desired, and by the employment of the constructions previously described, it will be seen that the latch ring, together with the three auxiliary thread feeding fingers 21, 22 and 23 can be swung upwardly on the pivot pin 6a, the feeding fingers being thereby disengaged from the upper ends of the rod 40, and the lugs 48, on the links 47, connected with the rods 43 and 45. The sinker cap 50, will obviously be provided 40 with not only the usual cam portion indicated at 51, in its groove for operating the sinkers at knitting station 4, in the usual manner, but will also be provided, as shown in Fig. 5, with additional cam portions indicated at 52, 53 and 54, 45 corresponding to the positions of the auxiliary cams 18, 19 and 20, so as to reciprocate the sinkers in cooperation with the knitting of stitches at stations 2, 3 and 4, by auxiliary knitting cams 18, 19 and 20. 50

I will now describe the operation of the machine for the knitting of a stocking having a top portion which is knit with four body threads and the formation of four courses simultaneously in each revolution of the needle cylinder, an elastic 55 thread being fed to selected needles, in this instance every fourth needle, in plating relation with one body thread fed to all the needles at the same knitting station, to wit, station, 1, and being knit continuously throughout the courses 60 forming the top. In knitting the top of the stocking in this manner, the pattern wheel 31, will be in position to allow all of the auxiliary cams 18, 19 and 20, and their respective thread feeding fingers 21, 22 and 23, to be brought into 65 operative position for knitting at stations 2, 3 and 4. The main body thread feeding finger 12, will be supplied with a body thread 13, and the auxiliary thread guides 21, 22 and 23, will be likewise supplied with body threads indicated at 13a, 70 13b and 13c in Fig. 9. The thread feeding finger 10, at knitting station 1, will be supplied with elastic thread, either rubber thread or preferably Lastex, under tension sufficient to reduce the diameter of the plain knit courses of the top after 75

they leave the needles so that the fabric is drawn into vertically disposed parallel rib-like ridges simulating rib knit fabric, so that the plain knit top will have both the appearance and form-fitting effect of an ordinary rib knit top, while the floats of the elastic thread on the inner face of the fabric will form horizontally disposed substantially continuous spiral beads, the individual coils of which will be separated by three intervening courses, so as to permit these beads to very slightly indent the flesh of the wearer and provide a self-supporting function to hold the leg of the sock from slipping downward on the leg. The large number of coils of this bead on the inner face of the top, and their separation from each other, enables each coil to act independently, so that the cumulative effect of this spiral bead is sufficient to insure the top of the sock remaining in position on the leg without slipping downward, with a minimum of tension of the elastic thread, and without any perceptible effect on, or inconvenience to the wearer. Referring to Fig. 9, and understanding that the cylinder with its needles will move in the direction of the arrow, with respect to the cam ring, all the needles will be slightly raised by the main knitting cam element 9b, preparatory to being drawn down by the cam elements 9 and 9a, which will act upon the butts 7a and 8a of the selected needles, but will engage the shoulders 7b and 8b, of the intermediate needles. Thus, when the needles come to the feeding finger 10, for the rubber thread, the selected needles without shoulders, will receive in their hooks the rubber thread which will not be fed to the remaining needles. As the needles pass the finger 12, the hooks of all the needles will receive the body thread 13, the selected needles therefore drawing loops composed of the body thread and the rubber thread, while the remaining needles will draw loops of the body thread only, at knitting station 1, the rubber thread being floated from one selected needle to the next, and behind the intervening needles with shoulders 7b and 8b, and thus the elastic thread will be floated on the inner face of the fabric. At knitting station 2, all of the needles are raised before they approach the feeding finger 21, and take the second body thread 13a, in their hooks, as they are drawn down by the auxiliary knitting cam 18, which acts only upon the butts of all of the needles, so that a second course of stitches composed of thread 13a, is formed, which is knit into the stitches of the preceding course containing the body thread 13, and having the elastic thread 11, at the spaced wales formed by the selected needles. At station 3, all of the needles are again raised to receive the third body thread 13b, from the thread finger 22, in their hooks, and all of the needles are drawn down by the second auxiliary cam 19, to form a third course of stitches from the thread 13b, which are knit into the stitches of the preceding course formed by thread 13a. The needles are then raised and pass to the fourth knitting station, where they receive in their hooks the fourth body thread 13c, from the thread finger 23, and all of the needles are drawn down by the auxiliary knitting cam 20, to form a fourth course of stitches from the body thread 13c, knit into the stitches of the course formed by the thread 13b. The needles are then raised, and pass to the first knitting station where a course of stitches is formed from the body thread 13, with the elastic thread 11, knit with the body thread in spaced wales by the selected needles, and the consecutive courses are formed from the body threads 13a, 13b and 13c, knitting on all the needles as previously described.

It will thus be seen that the knitting of the elastic top proceeds very rapidly, since four courses are knit with every revolution of the needle cylinder, until the desired length of the top has been produced, and it is desired to knit the leg portion of the stocking. At this point, the thread guide 10, for feeding the elastic thread is thrown out of operation under the control of the pattern mechanism by any of the usual means employed, and indicated in dotted lines at Fig. 1, for example, after which the leg portion of the stocking can be knit, if desired, by multiple course plain knitting, four courses being knit at a time, by permitting the auxiliary cams and other associated thread feeding fingers to remain in operative position. Obviously, the leg portion of the stocking could be knit by consecutive single courses with a single thread, if desired, by throwing all of the auxiliary cams and their associated feeding fingers out of operative position, or it could be knit by multiple knitting by the formation of two courses at each revolution of the cylinder, by throwing out of operation two of the auxiliary cams and their associated feed fingers, as the knitting cams 18, 19 and their feed fingers 21, 22, so that the multiple courses would be knit only at stations 1 and 4 for example. Or the leg could be knit by the formation of three courses simultaneously by throwing out of operation one of the auxiliary knitting cams as the cam 20, for example, and its associated thread feeding finger 23, in which case the multiple courses would be formed at stations 1, 2 and 3. The type of knitting to be employed in the leg of the stocking, and which would in all probability, be followed throughout the foot portion between the heel and toe pocket, can readily be secured by providing the cam wheel 31, with the appropriate cam grades 33, 34 and 35.

After knitting the leg portion of the stocking of the desired length, any of the auxiliary cams and other feeding fingers which have been operating during the formation of the leg are thrown out of operation, and it is desirable, although not necessary, to knit one or more complete circular courses with the knitting thread 13, and main knitting cam 9a, after which the heel pocket is knit by reciprocating work, and narrowing and widening in the usual manner, by means of the thread 13, and the main knitting cam in the usual manner. If desired, body thread finger 12, may be thrown out of operation and another finger at the throat plate carrying a heavier thread, may be brought into operation for knitting the heel pocket, or the heel pocket may be knit with the body thread 13, and an additional thread or threads, as desired.

After knitting the heel pocket, circular knitting is again resumed, preferably by multiple courses, using the main knitting cam and one or more of the auxiliary cams, and their associated feed fingers, thus forming the foot of the stocking by multiple feeding and plain knitting, with either two, three or four threads, as desired.

Immediately before the commencement of knitting of the toe pocket, I prefer to throw out of operation the auxiliary cams and their associated fingers used in knitting the foot, and knit a few looping courses, using only the main knitting cam and the body thread 13, or other body thread from a throat plate feed finger, after

which the toe pocket is knit in the usual manner with a single thread by reciprocating work and narrowing and widening as described by reference to the heel pocket, and the stocking is completed by looping on the upper half of the foot, the meeting edges of the toe pocket and the foot portions, in the usual manner. The toe pocket also may be formed of the thread 13, or a heavier thread or threads, if desired.

10 The entire stocking is therefore knit as a unitary fabric, including the plain knit top portion with the incorporated elastic thread, which forms an elastic form-fitting and self-supporting top for the stocking, and holds it in position

15 on the leg without the necessity of using a garter.

The upper edge of the top may be finished in any desired manner, for example, by a turned and sewed welt, or by the formation of a selvage or anti-ravel course or courses, of single thickness, in any desired manner.

It will be obvious that in multiple course knitting body threads of the same or different colors may be employed; and where different colors are used, pleasing striping effects can be simultaneously obtained. It will also be understood that while in the accompanying drawings, I have only shown a single thread feeding finger for each auxiliary cam, a plurality of feeding fingers may be provided for each of these auxiliary cams, where found necessary or desirable, and operated under the control of the pattern cam, so as to employ at each knitting station, body yarns of different characteristics, as to material, thickness or color, and shift one of the thread fingers 30 for any knitting station out of operation, and another one into operation to produce color effect or different character of fabric, at different portions of the multiple knitting, as may be desired.

It will be understood that my invention is not limited to the specific details and formation of parts herein shown, and described in the embodiment selected by me for purposes of illustration, as variations may be made therein, in the manufacture of machines embodying the invention, and within the scope of the following claims.

What I claim and desire to secure by Letters Patent is:

1. A circular plain knitting machine having a single circular series of independently movable needles provided with cam engaging butts, certain needles being provided with selecting shoulders adjacent to the butts thereof, a plurality of knitting cams, located at different points around the series of needles, means adjacent to one of said cams for engaging said selecting shoulders and drawing down certain of said needles and leaving selected needles at a higher level than the remaining needles, separate thread feeding devices adjacent to said cam for feeding an elastic thread to the hooks of said selected needles, and an inelastic thread to the hooks of all of the needles, and separate thread feeding mechanism adjacent to each of the other cams for feeding a separate inelastic thread to the hooks of all of the needles, and means for moving each of said last mentioned cams and their associated thread feeding mechanism into and out of operative position.

2. A circular plain knitting machine having a single circular series of independently movable needles provided with cam engaging butts, certain needles being provided each with a selecting shoulder above and of less radial extent than the butts thereof, a plurality of knitting cams, located at different points around the series of

needles, means adjacent to one of said cams for engaging said selecting shoulders and lowering certain needles to bring selected needles to a higher level than the remaining needles, separate thread feeding devices adjacent to said cam for feeding an elastic thread to the hooks of said selected needles and an inelastic thread to the hooks of all of the needles, and separate thread feeding mechanism adjacent to each of the other cams for feeding a separate inelastic thread to the hooks of all of the needles, and means for moving the said thread feeding mechanism for feeding the elastic thread to said selected needles adjacent to said first mentioned cam into and out of operative position.

3. A circular plain knitting machine having a single circular series of independently movable needles provided with cam engaging butts, certain needles being provided each with a shoulder above and of less radial extent than the butts thereof, a plurality of knitting cams, located at different points around the series of needles, means adjacent to one of said cams for engaging said selected needles and lowering them so as to leave selected needles at a higher level than the remaining needles, separate thread feeding devices adjacent to said cam for feeding an elastic thread to said selected needles and an inelastic thread to all of the needles, and separate thread feeding mechanism adjacent to each of the other cams for feeding a separate inelastic thread to all of the needles, means for moving said elastic thread feeding mechanism for the said selected needles adjacent to said first mentioned cam into and out of operative position without interference with the other feeding mechanisms, and means for moving each of said last mentioned cams and its associated thread feeding mechanism into and out of operative position simultaneously.

4. A circular plain knitting machine having a single circular series of independently operable needles provided with butts, certain of said needles being provided each with a shoulder above and of less radial extent than the butt, and certain selected needles, spaced from each other by one or more shouldered needles, being without said shoulders, a main knitting cam for engaging the butts of said selected needles, and the shoulders of the remaining needles, to bring the hooks of said remaining needles to a lower level than those of the selected needles at the thread feeding position, separate thread feeding mechanism adjacent said cam, for respectively feeding a thread to said selected needles only, and a separate thread to all of the needles, a plurality of auxiliary knitting cams for engaging the butts of all the needles without operatively engaging said shoulders, and a separate thread feeding mechanism for feeding a different thread to all of the needles.

5. A circular plain knitting machine having a single circular series of independently operable needles provided with butts, certain of said needles being provided each with a shoulder above and of less radial extent than the butt, and certain selected needles, spaced from each other by one or more shouldered needles, being without said shoulders, a main knitting cam for engaging the butts of said selected needles, and the shoulders of the remaining needles, to bring the hooks of said remaining needles to a lower level than those of the selected needles at the thread feeding position, separate thread feeding mechanism adjacent said cam, for respectively feeding

- a thread to said selected needles only, and a separate thread to all of the needles, a plurality of auxiliary knitting cams for engaging the butts of all the needles without operatively engaging 6 said shoulders, and a separate thread feeding mechanism for feeding a different thread to all of the needles, and means for moving the thread feeding mechanism for the selected needles only, into and out of operative position.
- 10 6. A circular plain knitting machine having a single circular series of independently operable needles provided with butts, certain of said needles being provided each with a shoulder above and of less radial extent than the butt, and certain selected needles, spaced from each other by one or more shouldered needles, being without said shoulders, a main knitting cam for engaging the butts of said selected needles, and the shoulders of the remaining needles, to bring the hooks 15 of said remaining needles to a lower level than those of the selected needles at the thread feeding position, separate thread feeding mechanism adjacent said cam, for respectively feeding a thread to said selected needles only, and a separate thread to all of the needles, a plurality of auxiliary knitting cams for engaging the butts of all the needles without operatively engaging said shoulders, and a separate thread feeding mechanism for feeding a different thread to all of the 20 needles, means for moving the thread feeding mechanism for the selected needles only, into and out of operative position, and means for moving each of said auxiliary cams and its associated thread feeding mechanism into and out of operative position.
- 25 7. A circular plain knitting machine having a single circular series of independently operable needles provided with butts, certain of said needles being provided each with a shoulder above and of less radial extent than the butt, and certain selected needles, spaced from each other by one or more shouldered needles, being without said shoulders, a main knitting cam for engaging the butts of said selected needles, and the shoulders 30 of the remaining needles, to bring the hooks of said remaining needles to a lower level than those of the selected needles at the thread feeding position, separate thread feeding mechanism adjacent said cam, for respectively feeding a thread to said selected needles only, and a separate thread to all of the needles, a plurality of radially movable auxiliary knitting cams located at different positions around said series of needles, and means for holding said cams when in operative position out of operative relation with said shoulders, and in position to engage the butts only of all of the needles, and a separate thread feeding 35 mechanism for each knitting cam for feeding a different thread to all of the needles.
- 35 8. A circular plain knitting machine having a single circular series of independently operable needles provided with butts, certain of said needles being provided each with a shoulder above and of less radial extent than the butt, and certain selected needles, spaced from each other by one or more shouldered needles, being without said shoulders, a main knitting cam for engaging the butts of said selected needles, and the shoulders of the remaining needles, to bring the hooks of said remaining needles to a lower level than those of the selected needles at the thread feeding position, separate thread feeding mechanism adjacent said cam, for respectively feeding a thread to said selected needles only, and a separate thread to all of the needles, a plurality of radially movable auxiliary knitting cams located at different positions around said series of needles, and means for holding said cams when in operative position out of operative relation with said shoulders, and in position to engage the butts only of all of the needles, and a separate thread feeding mechanism for each knitting cam for feeding a different thread to all of the needles.
- 40 9. A circular plain knitting machine having a single circular series of independently operable needles provided with butts, certain of said needles being provided each with a shoulder above and of less radial extent than the butt, and certain selected needles spaced from each other by one or more shouldered needles being without said shoulders, a main knitting cam constructed and positioned to engage the butts of said selected needles and the shoulders of the intervening needles and leave their hooks below the hooks of the selected needles, at the thread feeding position, means for separately feeding an elastic thread into the hooks of the selected needles and for feeding an inelastic thread to the said intervening needles, a plurality of auxiliary knitting cams at different knitting stations around the circular series of needles movable into and out of operative position and supported when in operative position in position to engage the butts only of all of the needles, a thread feed mechanism adjacent to each of said auxiliary cams for feeding an inelastic thread to all the needles, and means adjacent to each of said auxiliary knitting cams, operatively connected therewith and with its cooperating thread feed mechanism for throwing them into and out of operative positions.
